EMBROIDERY NEEDLE

Filed Aug. 25, 1920

UNITED STATES PATENT OFFICE.

FENNER B. BAKER, OF NEW YORK, N. Y., ASSIGNOR, BY MESNE ASSIGNMENTS, TO SUPERIOR HAND EMBROIDERER CORPORATION, OF NEW YORK, N. Y., A CORPORATION OF NEW YORK.

EMBROIDERY NEEDLE.

Application filed August 25, 1920. Serial No. 405,943.

To all whom it may concern:

Be it known that I, FENNER B. BAKER, citizen of the United States, residing at New York, in the county of New York and State of New York, have invented certain new and useful Improvements in Embroidery Needles, of which the following is a specification.

This invention has relation to embroidery needles of the type for making tufted stitches, and has for an object to provide a curved needle carrying the thread with means for reciprocating the needle so that the device may be carried forward, step by step to form the stitch without the necessity of auxiliary mechanism to produce lateral movement of the needle as in other devices heretofore provided.

Another object of the invention is to provide an improved means for limiting and regulating the length of tufted stitch taken by the device.

A still further object of the invention is to provide an improved tension device for grasping the thread during a return movement of the needle.

In addition to the foregoing this invention comprehends improvements in the details of construction and arrangement of parts to be hereinafter described and particularly set forth in the appended claims.

In the accompanying drawings in which similar and corresponding parts are designated by the same characters of reference throughout the several views in which they appear,

Figure 1 is a view in perspective of an embroidery needle constructed in accordance with my invention.

Figure 2 is a view thereof in front elevation.

Figure 3 is a view in vertical section.

Figure 4 is a transverse section taken on the line 4-4, of Figure 2.

Figure 5 is a detailed view of the needle, and

Figure 6 is a fragmentary view of part of the tension device.

With reference to the drawings, 10 indicates the stationary element of the device consisting of a tubular portion formed at one end with a lateral flattened extension 11 forming the presser foot, and having a

slot 12 therein. The reciprocal or needle carrying element is shown at 13 and is likewise tubular and adapted to slide within the member 10. The wall of the member 10 is formed with a longitudinal slot 14 adjacent the presser foot and the wall of the member 13 is cut away to form a lip 15 struck outwardly to enter the slot 14 and thus form a stop to limit relative movement of the parts. A lip 16 is struck inward from the cutaway portion of the member 13 and an opening 17 is formed in the wall of said member 13 below the lip 16. Said lip 16 is apertured to receive a rod 18 upon the lower end of which a laterally extending loop 19 is formed. The rod 19 is extended throughout the length of the device and securely connected to the reduced portion 20 of a handle 21, said reduced portion loosely entering the upper end of the member 13. A longitudinal slot 22 is formed in the wall of the member 13 at its upper end, and lateral notches 23 are formed in the wall at opposite sides of said slot 22 and preferably in staggered relation. A pin 24 passing through the slot 22 and entering the handle 21 forms a means for preventing relative rotation of the handle and member 13. A regulating device is provided consisting of a sleeve 25 which encompasses the upper end of the member 13 and is provided with an inwardly and radially extending finger 26 to enter the slot 22. I next provide a needle indicated at 27 which is curved and formed with the semi-cylindrical tang 28 of a diameter small enough to enter the tubular member 13, struck out portions 29 being formed to engage the beveled lower end of said member 13 to limit inward movement of the needle. An opening 30 is formed at a point adjacent the juncture of the needle portion and tang 28 so that when the parts are assembled the opening 30 will be opposite the previously mentioned opening 17.

In use, the thread is inserted through the opening 17, then through the loop 19, then through the opening 30 passed downward along the channel of the needle and finally through the eye 31 thereof at the lower end. The portion 10 is grasped in one hand and the presser foot rested upon the material to be embroidered. The handle 21 is then

grasped by the other hand and moved downward causing the needle to penetrate the material and carry the thread with it. Upon a subsequent withdrawal of the needle from the material a portion of the thread will be left behind to form a loop or tuft on the other side. By repeated operations a series of tufts are formed side by side owing to a gradual sliding movement of the entire device resulting primarily from the curved formation of the needle. Apparently there would be as much rearward movement of the member 10 upon a withdrawal of the needle as there would be forward movement accomplished during the insertion of the needle with the negation of the thought that a continuous travel of the member 10 in one direction would ensue. Practically, however, there is a resultant and continued, but uniform lateral movement of the member 10 in one direction forward, that is, the direction to which the presser foot points because of the fact that the rearward movement of the presser foot accomplished by withdrawal of the needle is slightly less than the previous forward movement occasioned by the insertion of the needle, due to friction between the presser foot and the material. It will be observed that upon a withdrawal stroke of the needle carrying member the handle and rod will first move up until the loop 19 engages the thread against the lip 16 and further movement will carry the entire member 13 and needle upward. In this manner the intermittent tensioning of the thread, and operation necessary in devices of this character is positively and effectively accomplished. For regulating the length of the tuft or loop the sleeve 25 is manipulated by rotating the same to bring the finger 26 within the slot 22. The sleeve is then shifted along the member 13 to the desired point and then rotated again to enter the finger in one of the notches 23. It will be thus observed that relative movement between the members 10 and 13 is limited on the one hand by engagement between the sleeve 25 and upper end of the member 10, and on the other hand by engagement between the stop member 15 and the upper wall of the slot 14.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claims.

Having thus described my invention, what I claim as new and desire to secure by United States Letters Patent is:—

1. An embroidery needle including a holding means, a fabric engaging means forming

part thereof, a member supported by the holding means for reciprocation, a curved needle having a perforation at its pointed end and means on its other end for connection to the said member, whereby a thread may be inserted in said needle and upon repeated reciprocations of said member said needle caused to make tufted stitches and feed the device along the fabric in the direction of the concave side of the needle, and means to grip the thread upon movement of the member in one direction and to release the thread upon a reverse movement of said member.

2. An embroidery needle including a holding means, a member mounted therein for reciprocation, a presser foot formed on said member, a curved needle carried by said member operating through the presser foot, whereby a thread carried by the needle may be fed into a fabric in tufted stitches and the device carried along the fabric by repeated reciprocations of said member, means to grip the thread upon movement of the member in one direction and to release the thread upon a reverse movement of said member and an adjustable stop on the member whereby the needle point may pass below the presser foot to a greater or less extent.

3. An embroidery needle comprising a tubular holder, a tubular member reciprocable within the holder, a presser foot formed on the said holder, a curved needle, a spring tang substantially semi-circular in cross section formed on one end of the needle to enter said tubular member, and means to alternately grip and release a thread carried by the needle upon reciprocation of said tubular member.

4. An embroidery needle including a tubular holder, a tubular member reciprocable therein, a presser foot formed on the holder, a needle, a tang formed on one end of the needle of semi-circular form in cross section to enter one end of the tubular member, a stop formed on said tang to engage the said end of the tubular member to limit the extent of insertion of the needle into said tubular member, and means to alternately grip and release a thread carried by said needle upon reciprocation of said tubular member.

5. An embroidery needle including a holder, a presser foot formed thereon, a tubular member operating in the holder, a needle having a longitudinal channel in one side and an eye at its pointed end, a tang formed at the other end of the needle for insertion into the tubular member, said tang having a channel formed therein in opposed relation to the first channel, said needle having an opening extending transversely therethrough and located at the juncture of the two mentioned channels, whereby a thread may be inserted through said opening, then run along the needle channel and finally

passed through the eye, and means to alternately grip and release the thread upon reciprocations of said tubular member.

6. An embroidery needle including a tubular holder, a tubular member operating therein, said holder having a slot in one side, and said member having a perforation located behind said slot, a handle loosely connected to said member, means carried by the handle to guide a thread, a needle carried by the member, whereby a thread may be passed through the slot and perforation, through the guide and finally through the needle, and means operating in connection with the guide to grip the thread when the handle is raised, the thread being alternately gripped and released by reciprocation of the handle.

7. An embroidery needle including a tubular holder, a tubular member operating therein, a presser foot formed on the holder, said holder having a slot and the member having a perforation behind the slot, a handle loosely connected to the member, a rod carried by the handle, an eye formed on the rod, a lip formed on the member adjacent the perforation forming a guide for the rod, and a needle carried by the member, whereby a thread may be passed through the slot, perforation, eye and needle in the order named, and the thread gripped between the eye and lip when the handle is moved in one direction and released when the handle is moved in a reverse direction.

8. An embroidery needle including a tubular holder, a tubular member operating therein, the latter having a slot, a handle having a sliding fit in the member, a projection extending from the handle into the slot to prevent relative rotation of the handle and member, a rod carried by the handle and extending through said member, an eye on the free end of the rod, a lip formed

on the member forming a guide for the rod, said member having a perforation near the 45 lip, and a needle carried by the member whereby a thread may be inserted through the perforation, eye and needle in the order named, said eye engaging the thread against the lip to hold the thread when the member 50 is moved in one direction by means of the handle and said thread released when the handle is moved in a reverse direction.

9. An embroidery needle including an outer tubular holder, an inner tubular member 55 slidable therein, said holder having a longitudinal slot, and said member having a slot formed therein and the material at one end of the slot bent out to form a lift to engage one end of the first mentioned slot 60 to form a stop limiting separation of said holder and member, means on the member to engage the holder to limit movement thereof in an opposite direction, a needle secured to the member, and having an eye at 65 its pointed end whereby a thread may be inserted through the first and second mentioned slots and through the eye of the needle, and means to alternately grip and release the thread during reciprocation of 70 the member.

10. An embroidery needle including a tubular holder circular in cross section, a member 75 slidable therein of tubular construction and circular in cross section, the holder having a longitudinal slot cut therein, a lip formed on the member entering said slot to limit relative movement of the holder and member, both in a longitudinal and circumferential direction, a needle carried by the member, and means to alternately grip and release a thread upon reciprocation of the member.

In testimony whereof affix signature.

FENNER B. BAKER.
